INVENTOR.

EDWIN F. HULBERT

Louis Scearle
ATTORNEY.

UNITED STATES PATENT OFFICE.

EDWIN F. HULBERT, OF MILWAUKEE, WISCONSIN, ASSIGNOR TO PEISTER & VOGEL LEATHER COMPANY, OF MILWAUKEE, WISCONSIN, A CORPORATION.

DEVICE FOR WRINGING WET LEATHER.

Application filed September 24, 1921. Serial No. 503,056.

To all whom it may concern:

Be it known that I, EDWIN F. HULBERT, a citizen of the United States, and resident of Milwaukee, in the county of Milwaukee and 5 State of Wisconsin, have invented a certain new and useful Improvement in Devices for Wringing Wet Leather, of which the following is a specification.

The invention relates to a device for 10 wringing wet leather.

Heretofore in wringing out wet leather it has been customary to use an apparatus in which half of the hide is wrung out during one operation and then the other half wrung 15 out during another operation, necessitating a rehandling of the hide for a complete wringing. The object of the present invention is to provide a hide-wringing device in which the entire wringing operation is 20 carried out without rehandling the hide.

A further object of the invention is to provide a hide-wringing device in which the hide is placed on a movable platen which is moved to bring the hide into contact with a 25 wringing roller and then by tilting said platen the hide is brought into contact with another wringing roller to accomplish the wringing operation.

The invention further consists in the several features hereinafter set forth and more particularly defined by claims at the conclusion hereof.

In the drawings: Fig. 1 is a side view of 35 a device embodying the invention; Fig. 2 is a front view thereof, parts being shown in section; Fig. 3 is a section taken on the line 3—3 of Fig. 2, with the platen in one of its wringing positions; Fig. 4 is a detail plan view of the platen.

In the drawings the numeral 5 designates 40 the frame of the machine, 6 a power pulley drivingly connected through a suitable clutch 7 with a shaft 8 carrying a gear 9 meshing with a gear 10 and a gear 11 meshing with a gear 12. The gear 10 is mounted 45 on a shaft 13 which carries a sprocket 14 connected by a chain 15 to a sprocket 16 on a shaft 17.

The shaft 17 carries a gear 18 meshing 50 with a gear 19 on a shaft 20. The shaft 17 carries a sprocket 21 connected by a chain 22 with a sprocket 23 on the shaft 24 of a wringing roller 25. The shaft 20 carries a sprocket 26 connected by chain 27 with a sprocket 28 on the shaft 29 of a wringing 55

roller 30. As the shaft 20, due to the gearing connection 19, 18, revolves in the opposite direction to that of the shaft 17, the roller 25 is rotated in the reverse direction to that of the roller 30. Each of the shafts 60 for the wringing rollers are mounted in bearing boxes 31 yieldingly held in a lower position by means of springs 32.

A platen for the hide is formed by side members 33 and shafts 34, 35 and 36. Shafts 65 34 and 35 carry pressing rollers 37 and 38, respectively, and gears 39 and 40, respectively, at their ends while shaft 36 forms a pivot about which the platen may tilt so as to bring either the gears 39 into driven engagement with gears 41 on the shaft 24, or the gears 40 into driven engagement with gears 42 on the shaft 29. An endless apron or belt B passes over the rollers 37 and 38 and forms a receiving and discharge table 70 for the hide H, as well as a guide for it during the wringing operation. The shaft 36 is journalled in slide bearing blocks 43 mounted in inclined guides 44 so as to bring the platen from its lower hide-receiving position, shown in Fig. 1, to its operative position, shown in Fig. 2, and for this purpose I use sets of toggle links 45 and 46 and connecting rods 47 operatively connected to the joints of these links and to crank 80 disks 48 mounted on a shaft 49 upon which the gear 12 is loosely mounted. The gear 12 is adapted to be drivingly connected with the shaft 49 by means of a pin clutch including a pin 50 slidably mounted in a collar 51 85 keyed to the shaft 49 and moved by a spring 53 into locking engagement with either one of two recesses 54 in the hub of the gear 12, said pin being automatically withdrawn from the gear 12 when either one of the 90 cams 55 on a rod 56 are positioned in the groove 57 in the collar so as to engage a groove 58 in the pin 50 to draw it out of engagement with the gear 12, which action occurs after the shaft 49 has made about 95 half a revolution, as indicated in Fig. 3.

The rod 56 is normally urged upwardly by means of a spring 58 and it is connected to an arm 59 on shaft 60 operated by a treadle 61. When the lower cam 55 is moved out 100 of engagement with the pin 50 on a depression of the treadle, the platen is brought to its elevated position and the upper cam 55 then moves the pin out of engagement with the pulley. On a release of the treadle the 110

upper cam 55 is moved out of engagement with the pin 50 which engages the gear 12 and the platen is moved from the position shown in full lines in Fig. 3 back to its lowered position, at which time the lower cam 55 disengages the pin 50 from the gear 12.

When the platen is in its upper position it may be tilted in the manner previously described so that one set of wringing rollers, such as 30 and 38, and then the other set of wringing rollers 25 and 37 are driven through the gearing connections previously described. To effect this tilting of the platen, I provide cam shafts 62 at each end of the machine carrying cams 63 and 64 and I connect these up for conjoint operation from either one of two shafts 65 by means of gears 66 and 67 connecting each shaft 62 with the adjacent shaft 65 and by means of sprockets 68 on said shafts 65 connected by a chain 69, each of the shafts 65 having a hand lever 70 for turning it which, through the gearing connection just described, causes a rotation of both of the shafts 65 and the cam shafts 62. When one of the levers 70 is turned in one direction the cams 66 come into engagement with the members 33 of the platen, causing its front end to tilt upwardly to bring the gears 40 into mesh with the gears 42 and when one of the levers 70 is turned in the opposite direction the cams 67 come into engagement with the members 33 of the platen, causing its rear end to tilt upwardly to bring the gears 39 into mesh with the gears 41.

With this construction, when the platen is in its lower position the hide is placed thereon and on a depression of the treadle 61 the platen is raised to a wringing position. Then by tilting the platen to bring the gears 40 and 42 into mesh while these gears are revolved through the driving connection with the shaft 8, the lower half of the hide, as shown in Fig. 3, is wrung between the rollers 30 and 38 and as the upper run of the apron B moves toward the left. Then by tilting the platen to bring the gears 39 and 41 into mesh the travel of the apron B is reversed and the other half of the hide is wrung between the rollers 35 and 37. Thus the whole hide is wrung out and the platen then lowered for the removal of the hide. The wringing operation is thus quickly accomplished with the minimum amount of handling of the hide.

I desire it to be understood that this invention is not to be limited to any specific form or arrangement of parts except in so far as such limitations are specified in the claims.

What I claim as my invention is:

65 1. In a leather-wringing device, the com-

bination of a pair of oppositely driven wringing rollers, a platen provided with rollers and an apron running over said rollers and upon which the hide is placed, means for moving the platen from hide-receiving position to a position against said wringing rollers, means for tilting the platen to bring the hide thereon into position for wringing engagement with first one and then the other of said wringing rollers, and means for drivingly connecting one of the rollers on the platen with the wringing roller with which the hide is in contact.

2. In a leather-wringing device, the combination of a pair of oppositely driven wringing rollers, a platen provided with rollers and an apron running over said rollers and upon which the hide is placed, means for moving the platen from hide-receiving position to a position adjacent said wringing rollers, and means for alternately tilting the platen to bring the hide thereon into position for wringing engagement with first one and then the other of said wringing rollers.

3. In a leather-wringing device, the combination of a pair of oppositely driven wringing rollers, a platen provided with rollers and an apron running over said rollers and upon which the hide is placed, means for moving the platen from hide-receiving position to a position adjacent said wringing rollers, means for tilting the platen to bring the hide thereon into position for wringing engagement with first one and then the other of said wringing rollers, and means for driving the apron when the platen is in either of its tilted positions.

4. In a leather-wringing device, the combination of a pair of oppositely driven wringing rollers, a hide support movable from hide-receiving position to a position adjacent said rollers and including rollers, means for tilting said support, when in position adjacent said wringing rollers, to bring the hide into engagement with first one and then the other of said wringing rollers, and means for drivingly connecting one of the rollers on said support with the wringing roller with which the hide is in contact.

5. In a leather-wringing device, the combination of a pair of oppositely driven wringing rollers, a hide support movable from hide-receiving position to a position adjacent said rollers, means for tilting said support, when in position adjacent said rollers, to bring the hide into engagement with first one and then the other of said wringing rollers, and means for moving the hide longitudinally while it is being acted upon by said wringing rollers.

6. In a leather-wringing device, the combination of a pair of oppositely driven

- spaced apart wringing rollers, a platen provided with spaced rollers and an apron running over said rollers and upon which the hide is placed, means for moving the platen 5 from hide-receiving position to a position adjacent said wringing rollers, means for tilting the platen to bring the hide thereon into engagement with first one and then the other of said wringing rollers, and a 10 gearing connection between each roller on the plateh and the wringing roller adjacent thereto, one of said gearing connections becoming operative when the platen is tilted to a wringing position.
- 15 7. In a leather-wringing device, the combination of a pair of oppositely driven wringing rollers, a platen beneath said rollers provided with rollers and an apron running over said rollers and upon which the 20 hide is placed, means for bodily moving the platen from hide-receiving position to wringing position, means for tilting the platen while in wringing position first to bring the hide thereon and one of the platen rollers into wringing engagement with one 25 of said wringing rollers and then bring the hide thereon and the other of said platen rollers into wringing engagement with the other of said wringing rollers, and means forming a driving connection between one 30 of said platen rollers and the wringing roller with which the hide is in contact.
8. In a leather-wringing device, the combination of a pair of oppositely rotating spaced wringing rollers and a hide support 35 relatively movable with respect to said rollers to bring the hide into engagement with first one and then the other of said wringing rollers, said support including spaced rollers having alternate driving connection 40 with said wringing rollers.

EDWIN F. HULBERT.
